UNITED STATES PATENT OFFICE

PAUL G. MASTERS, OF PHILADELPHIA, PENNSYLVANIA, ASSIGNOR TO PENNSYLVANIA WIRE GLASS COMPANY, OF PHILADELPHIA, PENNSYLVANIA, A CORPORATION OF NEW JERSEY

CORRUGATED GLASS WINDOW AND LIGHT

Application filed October 14, 1930. Serial No. 488,605.

The principal object of the present invention is to provide for reliably, economically and satisfactorily closing a window or skylight opening with more than one sheet of 5 corrugated glass of less width than the width of the opening and of length sufficient to span the opening.

Other objects of the invention will appear from the following description at the end of 10 which the invention will be claimed.

In describing the invention reference will be made to the accompanying drawings forming part hereof and in which

Figure 1 is a diagrammatic view of a window or skylight embodying features of the 15 invention.

Fig. 2 is a diagrammatic end view looking upward in Fig. 1 with the supporting feet omitted.

Fig. 3 is an elevational view of a filling 20 strip or supporting strip corrugated on one edge, straight on the other edge, and beveled.

Fig. 4 is a sectional view drawn to an enlarged scale and taken on the line 4—4 of 25 Fig. 1.

Fig. 5 is a sectional view taken on the line 5—5 of Fig. 1.

Fig. 6 is a diagrammatic view similar to Fig. 1 showing a modification.

Fig. 7 is a diagrammatic view similar to 30 Fig. 2 on line 7—7 of Fig. 6.

Figs. 8 and 9 are elevations of wide and narrow filling strips, respectively.

Fig. 10 is a cross section on an enlarged 35 scale on line 10—10 of Fig. 6.

Fig. 11 is a cross section on line 11—11 of Fig. 10, and

Fig. 12 is a cross section on line 12—12 of 40 Fig. 10.

In the drawings 1 indicates portions of a building construction having an opening. 45 2 indicates sheets of corrugated glass, either plain or wire, and they serve to close the opening. The sheets of corrugated glass are of a length sufficient to span the opening but they are narrower than the opening and it requires more than one of them to close it. In the modification shown in Figs. 1 to 5, inclusive, the sheets of corrugated glass at 50 their vertical edges underlap one and over-

lap the other of their neighbors and thereby assume positions inclined to the plane of the structure. Sealing compound 3 is arranged between the lapped portions of the sheets. Endwise tapering strips 4, flat on one edge 55 and corrugated on the other edge, seal the space at the ends of the sheets. 5 are spaced angle clips secured to the structure 1 which forms part of the building, and the sheets 2 are supported by them at the lower edges of 60 their lapped portions. Pads 6 are shown interposed between the angle clips and the sheets. 7 are brackets secured to the angle clips at the lapping portions of the glass. 8 indicates feet secured to the brackets and 65 they lap over the glass so as to hold it in against the building construction. The feet 8 are secured to the brackets by bolts and nuts 9, and the feet are provided with toes 10 which prevent their accidental turning 70 when the bolts are loose. At the top use is made of Z-shaped clips 11 secured to the roof structure and overlying the glass. 12 indicates flashing, and 13 is a pad similar to 75 the pad 6.

In the modification shown in Figs. 6 to 12, inclusive, one sheet of corrugated glass 2 overlaps the edges of the two adjacent sheets and all the sheets are adapted to be secured in an opening in a building or structure 1. Between the adjacent sheets 2 there are placed layers of sealing compound 3, such as strips of impregnated felt. The lower ends of the sheets 2 are sealed by relatively wide 80 sealing strips 44 and by relatively narrow sealing strips 444 which fit under the corrugations of the strips.

The sheets 2 are supported at their lower ends opposite the lapped joints by Z-shaped shelf clips 20 which fit over the lower edge 85 of the opening in structure 1. Riveted or otherwise secured to shelf clips 20 are shelves 21 through which pass threaded glazing pins 22 adapted to be secured to shelves 21 by nuts 90 23. As best seen in Fig. 12, glazing pins 22 have a slit 24 in the upper end thereof. Pins 22 are located opposite one of the corrugations in the outer sheet 2. There are setting pads 25 between pins 22 and sheets 2. There 95 100

are also setting pads 26 between shelves 21 and the ends of sheets 2.

At their upper ends, sheets 2 are secured to building 1 by means of clips 27 and 28 which are attached together by bolt 29 and nut 30. The inner clip 27 is secured to building 1 by bolt 31 and nut 32 or in any other convenient manner. The upper ends of sheets 2 are sealed and, at the same time, there is provided 10 a yielding connection between clip 28 and sheets 2 by placing therebetween angles 34 having felt linings 33 thereon. The entire upper connection is housed in flashing 12.

It will be obvious to those skilled in the art 15 to which the invention relates that modifications may be made in details of construction and arrangement and matters of mere form without departing from the spirit of the invention which is not limited to such matters 20 or otherwise than the prior art and the appended claims may require.

I claim:

1. A building construction having an opening, spaced supports secured to the building 25 construction, and arranged above and below the opening, sheets of corrugated glass closing the opening and held by the supports, said sheets of glass at their vertical edges lapping the neighboring sheets, and strips 30 of permanent shape flat on one edge and corrugated on the other edge and interposed between the supports and glass sheets.

2. A building construction having an opening, spaced shelf clips arranged below the 35 opening and secured to the building construction, sheets of corrugated glass closing the opening and overlying the shelf clips, said sheets of glass at their vertical edges lapping the neighboring sheets, shelves secured to the 40 shelf clips at the lapping portions of the glass, glazing pins secured to the shelves and lapping over the glass, and strips flat on one edge and corrugated on the other edge and interposed between the shelf clips and the 45 glass sheets.

3. A building construction having an opening, spaced shelf clips arranged below the opening, sheets of corrugated glass closing the opening and overlying the shelf clips, 50 said sheets of glass at their vertical edges lapping the neighboring sheets, shelves secured to the shelf clips at the lapping portions of the glass, relatively wide and narrow strips flat on one edge and corrugated on the other 55 edge and interposed between the shelf clips and glass sheets, glazing pins secured to the shelves and lapping over the glass, and clips secured to the building construction and overlying the lapped edges of the sheets at the top 60 thereof.

4. A building construction having an opening, spaced shelf clips arranged below the opening, sheets of corrugated glass closing the opening and overlying the shelf clips, 65 said sheets of glass at their vertical edge lap-

ping the neighboring sheets, shelves secured to the shelf clips at the lapping portions of the glass, relatively wide and narrow strips flat on one edge and corrugated on the other edge and interposed between the shelf clips and glass sheets, glazing pins secured to the shelves and lapping over the glass and nuts securing the glazing pins to the shelves. 70

5. A building construction having an opening, sheets of corrugated glass closing the opening and lapping the neighboring sheets, clips secured to said construction at the upper edge of said opening, second clips secured to said first mentioned clips and adapted to engage the ends of said sheets between the 75 clips, and an angle iron having a felt lining interposed between said second mentioned clips and the ends of the sheets. 80

6. A building construction having an opening therein, sheets of corrugated glass closing the opening and lapping the neighboring sheets, clips secured to said construction at the upper edge of said opening, second clips secured to said first mentioned clips and adapted to engage the ends of said sheets between the 85 clips, and an angle iron having a felt lining 90 interposed between said second mentioned clips and the ends of the sheets.
